PIPE VISE

Philip J. Brewington, San Antonio, Tex.

Application September 1, 1938, Serial No. 228,059

5 Claims. (Cl. 81—19)

This invention relates to pipe vises, and has for one of its objects the production of a simple and efficient pipe vise which is constructed in a manner whereby any size pipe may be firmly held thereby without the necessity of the operator employing a hand adjustment to accommodate the vise to pipes of various sizes.

A further object of this invention is the production of a pipe vise, the parts of which may be quickly adjusted by a simple operation to hold pipes of various sizes securely in position.

Other objects and advantages of the present invention will appear throughout the following specification and claims.

15 In the drawing:

Figure 1 is a side elevational view of the pipe vise;

Figure 2 is a top plan view thereof;

Figure 3 is a longitudinal sectional view taken 20 on line 3—3 of Figure 1;

Figure 4 is a fragmentary top plan view of the vise jaws carried by the base of the pipe vise;

Figure 5 is a vertical sectional view taken on line 5—5 of Figure 1;

25 Figure 6 is an enlarged side elevation of a portion of the pipe-gripping chain.

By referring to the drawing, it will be seen that 10 designates the base of the vise which is provided with an upstanding lug 11 near one end 30 to which lug is pivotally secured a frame 12 by means of a pivot connection 13 constituting a hinge, as shown in Figure 1. This frame 12 is substantially an inverted U-shaped structure, one end of which is provided with a depending 35 guiding neck 14, which neck 14 is in turn provided with a longitudinally extending channel 15 which is substantially T-shaped in cross-section.

A chain-engaging bar 16, T-shaped in cross-section, is slidably mounted within the channel 15 of the neck 14, the lower end of the bar 16 extending through the aperture 17 formed in the base 10. A coil spring 18 is secured to the upper end of the bar 16 and is also secured to the frame 12 to normally pull the bar 16 in an upward direction when pressure is relieved therefrom. A chain 19 is anchored at one end as at 20, to the base 10, and the opposite end is secured to the lower end of the bar 16, as at 21.

50 A plurality of pipe-supporting and engaging jaws 22 are secured to the base 10 intermediate the ends of the chain 19, as shown, and these jaws 22 are provided with V-shaped toothed notches 23 for the purpose of supporting a pipe 24, as shown. The chain 19 is preferably pro-

vided with teeth 25 upon the side faces thereof for facilitating the gripping of the pipe 24 as the chain 19 is tightly clamped about the pipe 24.

The base 10 is also provided with an upstanding rack 26 having an inclined toothed forward 5 face 27, as shown in Figures 1 and 3. This upstanding rack 26 is arranged beyond the depending neck 14, as shown in Figure 1, and is adapted to be engaged by the hook end 28 of the hook arm 29. This hook arm 29 is provided with 10 a bifurcated upper end 30 which bifurcated upper end 30 fits upon opposite sides of an eccentric 31 and is journaled upon a journal pin 32.

The eccentric 31 carries an operating handle 33 which projects forwardly, as shown in Figures 1 and 2, and is adapted to force the chain-carrying bar 16 downwardly as the handle 33 is moved downwardly for rotating the eccentric 31, thereby drawing the chain 19 tightly around the pipe 24 and locking the pipe in firm engagement 20 with the jaws 22. The eccentric 31 is provided with notches 34 upon the sides thereof, which notches 34 are adapted to be engaged by the inwardly extending fingers 35 carried by the bifurcated end of the hook arm 29 as the arm 33 is 25 swung upwardly in the direction of the arrow shown in Figure 1. The contact of the notches 34 with the fingers 35 of the hook arm 29 will cause the hook end 28 to be kicked or lifted out of engagement with the toothed forward face 27 30 of the upstanding rack 26, thereby permitting the frame 12 to be swung upon its pivot 13 upwardly in the direction of the arrow shown in Figure 1. The upward swinging of the handle 33 will cause the eccentric 31 to relieve pressure from the bar 16 and the coil spring 18 will 35 then pull the bar 16 upwardly and release the gripping action of the chain 19 from the pipe 24.

From the foregoing description, it will be seen that a very simple and efficient pipe vise has been 40 produced whereby the gripping portions for gripping the pipe will automatically conform to the contour of the pipe, such for instance as the chain, and adapt itself to various sizes of pipes without the necessity of the operator manipulating 45 minute and hand-controlled adjustments. Simply by placing the pipe 24 upon the jaws 22 and then by swinging the frame 12 over to the position shown in Figure 1, the hook arm 29 will automatically drop into engagement with the 50 toothed forward face of the rack 26. The handle 33 may be swung then downwardly bringing the eccentric 31 into frictional contact with the upper end of the bar 16 and forcing the same downwardly against the tension of the spring 18, caus- 55

ing the toothed chain 19 to firmly grip the pipe 24 holding the pipe 24 in position and also preventing the pipe from turning.

When it is desired to release the chain 19 from the pipe 24, the handle 33 is swung upwardly, releasing the pressure of the eccentric 31 from the bar 16 and the spring 18 will pull the bar 16 upwardly releasing the gripping action of the chain 19 from the pipe 24. Continued movement of the handle 33 upwardly will cause the notches 34 to be contacted by the fingers 35 and kick the hook arm 29 out of contact with the toothed face 27 of the rack 26 whereupon the frame 12 may be swung to a position to uncover the pipe 24 completely.

It should be understood that certain detail changes in the mechanical construction may be employed without departing from the spirit of the invention, so long as such changes fall within the scope of the appended claims.

Having described the invention, what I claim is:

1. A pipe vise of the class described comprising a base, a frame hingedly secured at one end to said base, said frame being of a substantially inverted U-shape, a chain connected at one end to said base, said frame having a depending neck, a sliding bar mounted upon said neck and engaging the opposite end of said chain, and means carried by said frame for moving said bar and tightly drawing said chain to a clamping position.

2. A pipe vise of the class described comprising a base, a frame hingedly secured at one end to said base, said frame being of a substantially inverted U-shape, a chain connected at one end to said base, said frame having a depending neck, a sliding bar mounted upon said neck and engaging the opposite end of said chain, an eccentric pivotally secured to said frame and engaging said bar for moving the bar to a position for drawing said chain about an article to be clamped as said eccentric is rotated, and a handle for actuating said eccentric.

3. A pipe vise of the class described comprising a base, a frame hingedly secured at one end to said base, said frame being of a substantially inverted U-shape, a chain connected at one end to said base, said frame having a depending neck, a sliding bar mounted upon said neck and en-

gaging the opposite end of said chain, an eccentric pivotally secured to said frame and engaging said bar for moving the bar to a position for drawing said chain about an article to be clamped as said eccentric is rotated, a handle for actuating said eccentric, a hook arm pivotally secured to said frame, and a rack carried by said base engageable by said hook arm for locking said frame in a closed position.

4. A pipe vise of the class described comprising a base, a frame hingedly secured at one end to said base, said frame being of a substantially inverted U-shape, a chain connected at one end to said base, said frame having a depending neck, a sliding bar mounted upon said neck and engaging the opposite end of said chain, an eccentric pivotally secured to said frame and engaging said bar for moving the bar to a position for drawing said chain about an article to be clamped as said eccentric is rotated, a handle for actuating said eccentric, a hook arm pivotally secured to said frame, a rack carried by said base engageable by said hook arm for locking said frame in a closed position, and means carried by the eccentric and adapted to engage said hook arm for automatically moving the hook arm to a released position as said eccentric is moved in one direction.

5. A pipe vise of the class described comprising a base, a frame hingedly secured at one end to said base, said frame being of a substantially inverted U-shape, a chain connected at one end to said base, said frame having a depending neck, a sliding bar mounted upon said neck and engaging the opposite end of said chain, an eccentric pivotally secured to said frame and engaging said bar for moving the bar to a position for drawing said chain about an article to be clamped as said eccentric is rotated, a handle for actuating said eccentric, an upstanding rack having an inclined toothed face, a hook arm pivotally secured to said frame and adapted to engage said toothed face of said rack for locking the frame in a clamped position, inwardly extending fingers carried by said hook arm near its upper end, and lug means carried by said eccentric for engaging said fingers and being adapted to kick said hook arm to a released position as said eccentric is moved in one direction.

PHILIP J. BREWINGTON. 50
